UNITED STATES PATENT OFFICE.

JOHN M. FLANNERY, OF DETROIT, MICHIGAN.

CARBURETOR.

Application filed April 7, 1922. Serial No. 550,491.

To all whom it may concern:

Be it known that I, JOHN M. FLANNERY, a citizen of the United States, residing at Detroit, in the county of Wayne and State 5 of Michigan, have invented certain new and useful Improvements in and Relating to Carburetors, of which the following is a specification.

This invention relates to a carburetor for 10 supplying carbureted air to an internal combustion motor.

One object of the invention is to provide a carburetor of relatively simple construction.

15 Another object of the invention is to provide a carburetor which effects proper mixtures of air and gasoline at all times independently of the engine speed or increases therein, whereby efficient operation, relatively quick pick-up in speed and maximum mileage is insured.

20 A further object of the invention is to provide an improved carburetor having a plurality of mixing tubes and a throttling means which is so arranged that it will, throughout its range of movement from closed to full open position and back to closed position insure the flow of the combustible charge from either or both mixing 25 tubes to either side of the throttling means, so that where a plurality of manifolds or a manifold having a plurality of branches are used, the mixture or charge flowing to each thereof will be of the same character.

30 Other objects of the invention will be apparent to those skilled in the art to which my invention relates from the following description taken in connection with the accompanying drawings, wherein—

35 Fig. 1 is an elevation of a carburetor embodying my invention.

Fig. 2 is a longitudinal section through the carburetor on the line 2—2 of Fig. 3.

40 Fig. 3 is a section on the line 3—3 of Fig. 1.

Fig. 4 is a section on the line 4—4 of Fig. 1.

Fig. 5 is a section on the line 5—5 of Fig. 1.

50 Fig. 6 is a section on the line 6—6 of Fig. 1.

Fig. 7 is a section on the line 7—7 of Figs. 4 and 6.

Fig. 8 is a section on the line 8—8 of Fig. 3.

55

Fig. 8 is a fragmentary sectional view on the line 8a—8a of Fig. 1.

Fig. 9 is a fragmentary view on the line 9—9 of Fig. 1, parts being broken away.

Fig. 10 is a perspective view of one of the levers for operatively connecting the throttle valve and the supplemental valve.

Referring to the drawings, 1 indicates a chamber, comprising a bottom wall 2 and side walls 3, arranged to hold gasoline or other combustible fluid and serve as a constant source of fuel supply for nozzles, 4, 5, to be later referred to. 6 indicates an air intake preferably of tubular shape in cross section. The air intake 6 may extend horizontally, its side and lower walls being preferably formed integrally with the bottom and side walls 2, 3, of the fluid chamber 1.

7 indicates a web extending transversely between the side walls of the air intake 6 (see Figs. 2 and 6), being formed integrally therewith, and co-operating with a wall 8 spaced from the bottom wall 2 (see Fig. 2) to form a conduit 9 leading from the lower portion of the chamber 1 to supply fuel to the nozzles 4, 5.

10 indicates a nipple formed integrally with and depending from the bottom wall 2 of the chamber 1. The inner wall of the nipple is screw threaded to removably receive at its inner end a fitting 11 and at its outer end a plug 12 having a head 13. The fitting 11 is formed with a duct 14 through which the fuel flows to the chamber 1. The wall for the upper portion of the duct 14 is cut away to form a seat for a valve 15 which is preferably a needle valve. The stem 16 of the valve 15 extends upwardly and is guided and operated in the manner to be later described. 17 indicates one or more ports formed in the wall of the nipple 10 and opening at their inner ends into the duct 14 therethrough. 18 indicates a coupling member constructed for connection with the nipple 10. As shown, the coupling 100 18 fits over and surrounds the nipple its side walls 19 being preferably shaped to

form a channel around the nipple to simultaneously supply fluid to all of the ports 17. The coupling 18 is formed with an opening 20, through which the reduced end of the 5 plug 12 extends for connection with the inner wall of the nipple 10. When so connected, the head 13 of the plug 12 engages the coupling 18 and clamps it in position around the nipple 10 and against the bottom 10 wall 2. The plug 12 is preferably bored out as shown at 21, a portion of such bore being screw threaded to adjustably support a valve stem 22 in the bore. The stem 22 is hollow and at its inner end it is formed 15 with one or more laterally extending ports 23, so that when the stem 22 is moved inwardly by its rotation, the ports will be positioned above the inner end of the plug 12 and thereby permit draining of the chamber 1 and conduits leading thereto. The coupling 18 is provided with a pipe section 18^a, to which a fuel supply pipe (not shown) is connected in a well known way.

The supply of the fuel to the chamber 1 25 is preferably controlled by a float which may comprise a hollow member 24. The float 24 surrounds the stem 16, being guided in its up and down movements thereby. 25 indicates a cover for the chamber 1. The cover 30 may be held in place by a plurality of cap screws 26, secured in aligned openings formed in lugs 27 carried by the wall 3 and cover 25. The central portion of the cover 25 is formed with an opening 28 in which the upper end of the valve stem 16 is 35 slidably supported. 29 indicates an annular boss provided on the cover 25 and surrounding the guide opening 28. The outer wall 40 of the boss 29 is screw threaded to permit the connection therewith of a thimble 30 which encloses but permits access to the upper end of the valve stem 16 for reasons that will later appear. 31 indicates pair of spaced lugs depending from the cover 45 25 and supporting between them, preferably at opposite sides of the stem 16, a pair of levers 32. The outer ends of the levers 32 engage the upper face of the float 24; the inner ends of the levers are disposed 50 between and engage a pair of spaced collars 33 and act therethrough to control the valve 16 due to rise and fall of the float 24. To permit of adjustment of the valve stem 16 relative to the float 24, whereby the fluid 55 supply may be properly controlled, the valve stem 16 is formed of two sections 16^a, 16^b, the latter being a sleeve carrying the collars 33 and adjustably fitting the section 16^a and adapted to be fixed in its adjusted position by a nut 16^c. By loosening the nut 16^c and engaging the slot in the free end of the sleeve 16^b (after the removal of the thimble 30) with a suitable tool, the sleeve 16^b 60 may be turned to adjust it longitudinally of the section 16^a.

34 indicates a valve, preferably of the butterfly type, disposed in the air intake or pipe 6 and movable or adjustable to open or close the passage through the intake a greater or lesser amount as conditions may 70 require; more particularly the valve is operated to close the passage through the intake at the time of starting the motor. The valve 34 is fixed to a shaft 35, which is mounted at its opposite ends in bearings 75 or openings formed in the wall of the intake 6. At one end outside of the intake, the shaft 35 is provided with a crank arm 36, which carries at its free end a clamping device 37 to which an operating connection 38 is connected in any well known manner. The connection 38 may be guided by a tube 39, which is supported by a bracket 40 mounted on a boss 41 (see Fig. 2) forming one bearing for the shaft 35. 80

I will refer to the nozzle 4 as the main supply nozzle, as it will be apparent from the drawings and the following description that the mixing tube for the nozzle 4 continuously supplies carbureted air to the engine or motor (not shown) except as such supply may be regulated or controlled by a throttle 42; whereas, the mixing tube for the nozzle 5 is normally closed and does not open to supply the carbureted air until 95 the throttle 42 is opened to or beyond a predetermined position, as will be later set forth.

The nozzle 4 comprises a tubular member 43. Near its upper end the tubular member is reduced as shown at 43^a and adjacent its reduced portion, its inner wall is contracted, as shown at 44, thereby forming at the lower end of the contracted portion a valve seat for a needle valve 45 and above 105 the contraction portion a cup shaped open end 4^a, from which the gasoline is discharged.

The lower end of the tubular member 43 is provided with screw threads, as shown 110 at 46 and such screw threaded end fits into a screw threaded opening 47, formed in the wall 8. The body portion of the tubular member 43 is preferably enlarged to form a shoulder against which the tubular member is tightened when its end 46 is positioned in the opening 47. 48 indicates an opening formed in the bottom wall 2 in alignment with the opening 47. The wall of the opening 48 is screw threaded 115 to detachably receive a plug 49; the plug being provided with a collar 49^a, which is tightened against the wall 2 when the plug is positioned in the opening 48. 49^b indicates a gasket interposed between the collar 49^a and the bottom wall 2 to prevent leakage. The plug 49 is formed with an opening 49^c in which the screw threaded 120 portion of a stem 50 of the needle valve 45 is adjustably supported. A gland 49^d may be 125

provided around the needle valve stem 50. As shown, the valve stem 50 extends through the tubular member 43 but is of such size as to permit the fuel to flow around it through the tubular member and through the orifice 44 when the valve is open. At its lower end the stem 50 may be provided with arms 50^a whereby it may be readily turned.

10 51 indicates a tubular boss formed integrally with and extending from the upper face of the wall 8, and arranged to support a tubular member 54, which forms one of the elements comprising the nozzle 5. As shown in the drawings, the opening 48 and boss 51 are arranged so as to support the tubular members 43 and 54, axially of the Venturi tubes, 52, 53, to be later referred to, with which they are respectively associated. At its upper end, the inner wall of the boss 51 is provided with screw threads to engage and support the screw threaded lower end of the tubular member 54. The tubular member 54 extends upwardly, its upper end terminating in the Venturi tube 53 preferably at a point slightly above the upper discharge end of the nozzle 4. The wall of the boss 51 is thickened at its lower end to form a bottom wall 55, and such bottom wall is formed with an opening 56, which leads through the wall 8 into the conduit 9. 57 indicates a supply tube having a screw threaded portion 58 engaging the screw threads provided on the walls of the opening 56, whereby it is rigidly supported. The tube 57 extends upwardly through the boss 51 and the tubular member 54, terminating in the latter at a point below the gas level which is maintained in the nozzle 5 by the chamber 1. As shown, the supply tube 57 is smaller in size than the boss 51 and tubular member 54, so as to provide around it an annular space 59 and a chamber 60 in the boss 51, in order that the fuel rising in the tube 57 may flow over its upper or discharge end and through the space 59 into the chamber 60 for a purpose to be later set forth. The lower end of the supply tube 57 is preferably enlarged to form a shoulder 61, which is tightened against the under face of the wall 8 when the tube 57 is positioned, the inlet end of the tube being shaped to form a seat 63 for a needle valve 62. 63 indicates an opening formed in the bottom wall 2 in alignment with the opening 56. The wall of the opening 63 is screw threaded to detachably receive a plug 64; the plug being provided with a suitable collar 65 which engages the wall 2 when the plug is positioned. 66 indicates a gasket interposed between the collar 65 and wall 2 to prevent leakage. 67 indicates an opening formed in and extending through the plug 64, the wall of the opening being provided with screw threads to engage screw threads provided on the stem 62^a of the needle valve 62, whereby the latter may be adjusted toward and from its seat to regulate the supply of fuel 75 to the tube 57. A gland 68 may be provided around the valve stem 62^a.

15 The walls of the upper portion of the air intake 6, adjacent its connection with the wall 3 of the chamber 1, are extended and 75 preferably terminate in a horizontal plane to form a seat for a conduit section indicated as an entirety at 69, and so shaped and arranged that (1) the side wall 3 of the chamber forms an end wall for the air intake 6 to direct the air upwardly and around the nozzles 4, 5, and (2) the nozzles 4, 5, are disposed in a plane extending diametrically of the conduit section 69 so as to center them with respect to the 80 Venturi tubes 52, 53. At their opposite sides, the intake 6 and section 69 are provided with lugs 70 formed with aligned openings through which suitable cap screws 70^a extend to secure the conduit section 69 90 to the air intake 6.

20 The conduit section 69 is preferably a casting. The lower portion of the section 69 is preferably elongated from side to side and provided with a transverse wall 69^a 95 arranged to form within said lower portion a relatively large mixing chamber 71 above the nozzle 5 and a relatively small mixing chamber 72 above the nozzle 4, the chamber 72 constituting the main mixing chamber 100 and the chamber 71 a supplemental or secondary mixing chamber. The upper portion of the casting is preferably contracted to form a main conduit 73 into which the carbureted air is delivered. The conduit 105 73 is connected in any desired manner with the intake manifold of the motor. The flow or supply of the carbureted air from the conduit 73 to the manifold is controlled by the throttle 42. The wall 69^a is curved and 110 co-operates with the adjacent side and end walls of the section 69 to form a seat for the upper portion of the Venturi tube 53 to support it concentric to the nozzle 5.

25 74 indicates a wall extending across the lower end of the chamber 72. The wall 74 is preferably formed integrally with the adjacent end and side walls of the intake 6 and is shaped to cooperate with the lower end of the wall 69^a to close the chamber 72 120 at its lower end. 75 indicates an opening formed in the wall 74 concentric to the nozzle 4 and serving as a seat for the Venturi tube 52. The Venturi tube 52 is preferably provided with a shoulder 52^a which 125 engages the upper face of the wall 74 so as to support the tube in the opening 75.

30 As shown in the drawings, the Venturi tubes 52, 53, are of a size to insure the discharge of the gasoline or fuel from the nozzle 130

zles as the air is drawn up through them. The tubes 52, 53, are supported so that their ends are disposed above and below the nozzles 4, 5, with their contracted portions in juxtaposition thereto. While I have shown one Venturi tube supported by the walls of the conduit section 69 and the other Venturi tube supported by a wall which is connected to and forms an integral part of the intake 10 6 and side wall 3, this is merely for illustrative purposes; the wall 74 may be connected to or formed integrally with the section 69 and both Venturi tubes may be supported by either the sections 69 or intake 6.

76, 76 indicate valves for admitting air from the intake 6 directly into the mixing chamber 72 through openings 77 formed in the wall 74 without passing through the 20 venturi and constituting in effect a by-pass. The walls of the openings 77 are shaped to form seats for the valves 76. The valves 76 preferably comprise balls which seat themselves by gravity. Each ball 76 is lifted by the vacuum created by the engine and permits air to pass to the mixing chamber 72, thereby preventing as rapid increase in suction effect as would take place if the air intake were of fixed area, and insuring 30 sufficient air supply in proportion to the vacuum created to provide a proper carbureting mixture with the gasoline being discharged from the nozzle 4.

The air passes through the by-pass valves 35 76 with relatively great velocity, and acts upon the carbureted air in or passing through the mixing chamber 72 to form a properly combustible charge. By this arrangement I am enabled to provide proper 40 mixtures of fuel for driving operations through a wide range of relatively low speeds with only the mixing tube 72 operating. As the opening of the valves 76 is controlled by the suction effect of the 45 engine they supply sufficient air for mixture with the carbureted air from the venturi 52, to form a properly mixed combustible charge in the mixing tube or chamber 72 accordingly as a larger quantity of carbureted 50 air is discharged thereto from the venturi 52.

In the preferred form of the construction, I provide two valves 76 preferably disposed between the Venturi tube 62 and the wall 55 69^a and at opposite sides of a plane cutting the axes of the Venturi tubes 52 and 53. However, a greater or lesser number of valves may be provided, if desired. By the 60 arrangement disclosed the sizes of each valve and valve seat may be relatively small and more sensitive control may be effected in insuring the admission of air in proportion to the suction effect at all times. Furthermore, it will be seen that I am enabled 65 to maintain the correct supply of fuel while

mixing it with enough air at all times to insure a properly mixed combustible charge for all running conditions, with resulting economical operation of the engine. As the balls are gravity operated, they are unseated at all times when the suction effect reaches a predetermined degree. The balls 76 are guided by the wall 69^a and the walls of the section 69 and venturi 52 as will be clear from Fig. 4. The balls 76 are limited 70 in their opening movement by a rod 79, preferably supported at its opposite ends in recesses 80 formed in the ends of a pair of screw plugs 81, fitting openings formed in the side walls of the conduit section 69. 80

82 indicates a valve for closing the discharge end of the supplemental or secondary mixing chamber or tube 71. The valve 82 is open for the purpose to be later set forth, at which time air will be sucked in from the air intake 6 and the air in turn will draw fuel from the jet 5 for mixing therewith. The valve 82 is preferably of the butterfly type. It may be secured to a rock shaft 83. The shaft 83 is preferably mounted at one end in a tubular boss 84 formed on and extending laterally from one wall of the section 69; its opposite end is mounted in an opening 85 formed in the metal which constitutes the wall 69^a between the tubes 71, 72. The shaft 83 extends through the boss 84 and carries at its outer end a crank 86 by means of which the valve 82 is operated. The hub of the crank 86 is preferably formed with an annular recess to form a 100 space around the shaft 83 for a coiled spring 87, one end of which may be secured to the crank and its other end anchored to a pin 88, as shown in Fig. 3. The pin 88 may serve as a stop to limit the movement of the 105 crank 86 under the influence of the spring 87 when the valve 82 is in the closed position (see Fig. 1). The spring 87 serves to maintain the valve 82 closed, but permits it to be opened in the manner to be later 110 described.

As shown, the throttle valve 42 is arranged to control the flow of the carbureted air from the main mixing tube and also from the supplemental or auxiliary mixing tube. I prefer 115 to use a butterfly type of throttle to control the conduit 73. The throttle valve 42 is preferably rigidly connected to a shaft 90 mounted at its opposite ends in the walls of the conduit section 69, one end of the shaft 120 being extended and carrying at its outer end a crank 91, whereby it may be operated through suitable devices (not shown) in the usual manner. As shown, the shaft 90 extends transversely of the conduit 73 and 125 is disposed in a plane which cuts the axes of the mixing tubes 71, 72 and nozzles 4, 5, therein. In such arrangement the throttle valve will properly control the flow of the carbureted air through the outlet conduit 130

73 when either or both mixing tubes are operating, so that the same character of mixture will pass one side of the valve 42 as passes the other side thereof. Accordingly, 5 it will be seen that where the conduit is connected to a plurality of manifolds or a manifold which has a plurality of branches, the same character of mixture will be supplied to each. This arrangement is particularly ad- 10 vantageous where the mixing tubes have different capacities as herein disclosed. By preference, both ends of the shaft 90 are ex- tended and may carry cranks either or both of which may be utilized for operating the 15 valve 42. Either or both cranks may be ad- justably connected to the shaft 90 to per- mit necessary take-ups and proper connec- tion of the operating devices therewith. 92 indicates a lug projecting from the wall of 20 the conduit section 69 and disposed in the path of movement of an element, such as a screw, carried by a lug integrally connected with a lever 94 (to be later referred to), whereby the movement of the valve 42 is 25 stopped at its closing position.

Means are provided for connecting the valves 42 and 82 together for operation in a predetermined relationship, whereby the latter is positively operated by the former 30 or through its operating means, to effect a supply of carbureted air from the supple- mental or secondary mixing tube 71 when an auxiliary supply is needed and in quanti- ties to meet the requirements of the motor 35 at any instant. The above referred to connecting means comprises the following in- strumentalities; the lever 94 (already re- ferred to) which is keyed or otherwise se- cured to the shaft 90. The outer end of the 40 lever 94 is formed with an elongated slot 95. 96 indicates a link formed in its upper end with an opening through which and the slot 95 a pin 97 projects to pivotally connect the link 96 to the lever 94. The pin 97 is shaped 45 to permit free pivoting of the link 96 and lever 94 as the latter is operated, but is adapted to be adjustably fixed to the lever 94 at either end of the slot 95 or at any point between said ends, accordingly as cir- 50 cumstances may require, for reasons which will later be explained. At its lower end the link 96 is provided with an elongated slot 98, through which projects a pin 99 carried by the free end of the crank 86, the pin 55 99 and slot 98 serving to pivotally and slid- ably connect the link 96 to the crank 86. The pivot pin 99 is preferably headed so as to engage the link 96 at either side of the slot and maintain these parts in connected 60 relationship. The positions of the inner end wall of the slot 95 relative to the shaft 90, the inner end wall of the slot 98 relative to the pin 97 and the pin 99 relative to the shaft 83 are such that if the pivot pin 97 is 65 positioned at the lower or inner end of the

slot 95, the upper end wall of the slot 98 will be in engagement with the pin 99, and upon the operation of the crank 91 to operate the valve 42, the operating connections will operate the valve 82 in unison there- 70 with, but by adjusting the pivot pin 97 end- wise of the slot 95 toward its outer end, (for example, as shown in Fig. 1) the connec- tions may be made to positively open the valve 82 at a later or earlier period in 75 the movement of the throttle valve 42 as may be desired or found necessary in the operation of the engine. The slot 95 per- mits the necessary adjustment of the connec- tions and the resultant adjustment of the 80 valves 42 and 82 relative to each other, whereby efficient and economical operation of the engine is effected.

100 indicates a supplemental gasoline well connected at its lower end by a duct 101 85 with the chamber 60. The well 100 and the duct 101 are formed in thickened portions of the walls for the chamber 1 and air in- take 6. The upper end of the well 100 is preferably enlarged and provided with 90 screw threads, whereby a plug or cap mem- ber 102 may be provided to close the well. The plug may be formed with an air inlet opening or duct 103 so that the gasoline in the well may be readily supplied to the 95 nozzle 5 by the suction effect of the engine.

As shown in the drawings, the supple- 100 mental well 100 is not connected directly with the float chamber 1, but is connected to the supplementary nozzle 5 from which it is supplied, the gasoline overflowing the tube 57 or passing directly through the port 57a. In operation, where the auxiliary valve 82 is suddenly opened and the vacuum of the 105 engine causes a sudden and large intake of air to pass the nozzle and draw all of the fuel filling the nozzle 5, the well 100 serves to provide an immediate additional supply of gasoline, sufficient to meet the engine needs. As the gasoline well 100 is con- 110 nected to the nozzle 5 and receives its sup- ply therefrom, it will remain empty until the valve 82 is closed, whereupon it will re- fill in the manner already described. The well 100 is of a size to hold a sufficient sup- 115 ply of gasoline to provide an ample charge of fuel from the nozzle 5 in the event the throttle 42 and valve 82 are opened to full open position; hence such supply will pro- vide the necessary fuel to insure a quick 120 pick-up in engine speed to the full limit of speed of the latter, if desired.

In the construction herein described, I 125 provide a carburetor in which the air and gasoline are supplied in proper quantities at all times, so that the engine may be prop- erly controlled to run on high, low and in- termediate speeds, and effect relatively quick changes in speeds. By providing a main mixing tube, a supplemental mixing 130

tube, and by-pass valves for automatically supplying air from the air intake to the mixing chamber, I am enabled to provide proper mixtures at all times, and to so reduce the vacuum effect on either or both nozzles that at no time will there be a failure of gasoline supply.

In my construction of carburetor it will be noted that I provide a relatively small mixing tube which is always open and a relatively large mixing tube which is normally closed but is caused to supply atomized fuel in correlation to the operation of the throttle whereby ample fuel is supplied as the speed of the engine increases. In such a construction the fuel supply is in proportion to the demands of the engine, being automatically supplied and shut off as the speed of the latter increases and decreases. This arrangement therefore provides relatively great flexibility in driving where the carburetor is associated with an automobile.

By providing two mixing tubes one of which augments the other, the main mixing tube is not called upon to supply all of the fuel required as the engine speeds up; hence when the engine speed increases the fuel supplied is augmented by the supplemental mixing tube 71, both tubes 71, 72, then supplying the required fuel. Accordingly I am enabled to operate the engine over a wide range of speeds and maintain at all times an ample supply of carbureted air.

It will be evident that many modifications of the apparatus can be made without interfering with the functions of the same or affecting the results accomplished; hence I wish to be understood that my disclosures and the description herein are purely illustrative and are not intended to be in any sense limiting, as widely differing embodiments and applications of the invention will suggest themselves to those skilled in the art to which my invention relates without departing from the spirit and scope thereof as defined by the appended claims.

What I claim is:

1. In a carburetor, the combination of a supply chamber, an air intake, an outlet conduit, a pair of mixing tubes each communicating with said intake and said conduit, a nozzle disposed in each said mixing tube connected with said chamber, a throttle for controlling the flow of carbureted air through said conduit, a valve for controlling the flow of carbureted air from one of said mixing tubes into said conduit, means for operating said throttle and said valve, and a valve mechanism for admitting air into one of said tubes independently of said communication of the latter tube with said intake.

2. In a carburetor, the combination of a

supply chamber, an air intake, an outlet conduit, a pair of mixing tubes each communicating with said intake and said conduit, a nozzle and a venturi disposed in each said mixing tube, each venturi being open at its lower end to receive air from said intake and each nozzle being connected with said chamber, a throttle for controlling the flow of carbureted air through said conduit, a valve for controlling the flow of carbureted air from one of said mixing tubes into said conduit, means for operating said throttle and said valve, and a valve mechanism for admitting air from said intake into one of said mixing tubes around the nozzle and venturi opening thereinto.

3. In a carburetor, the combination of a supply chamber, an air intake, an outlet conduit, a pair of mixing tubes each communicating with said intake and said conduit, a nozzle and a venturi disposed in each said mixing tube, each venturi being open at its lower end to receive air from said intake and each nozzle being connected with said chamber, a throttle for controlling the flow of carbureted air through said conduit, a valve for controlling the flow of carbureted air from one of said mixing tubes into said conduit, means for operating said throttle and said valve, and a valve mechanism for admitting air from said intake into one of said mixing tubes around the nozzle and venturi leading thereinto, the valve element for said valve mechanism comprising a member which is gravity seated and operated to open the valve when the vacuum is sufficient to overcome its weight.

4. In a carburetor, the combination of a gasoline supply chamber, an air intake, an outlet conduit, a pair of mixing tubes each communicating with said intake and said conduit, a nozzle disposed in each of said mixing tubes connected with said chamber, a valve for controlling the flow of carbureted air through said conduit, a valve for controlling the flow of carbureted air from one of said mixing tubes into said conduit, operating connections between said valves, means for operating one of said valves, and a valve mechanism for admitting air from said intake into one of said tubes independently of said communication between the latter tube with said intake.

5. In a carburetor, the combination of a gasoline supply chamber, an air intake, an outlet conduit a pair of mixing tubes each communicating with said intake and said conduit, a nozzle and a venturi disposed in each of said mixing tubes, each venturi being open at its lower end to receive air from said intake and each nozzle being connected with said chamber, a valve for controlling the flow of carbureted air through said conduit, a valve for controlling the flow of mixed carbureted air from one of said mix-

ing tubes into said conduit, operating connections between said valves, means for operating one of said valves, and a valve mechanism for admitting air from said intake into the other mixing tube around the nozzle and venturi opening thereinto.

6. In a carburetor, the combination of a supply chamber, an air intake, an outlet conduit, a pair of mixing tubes each communicating with said conduit, a nozzle disposed in each said mixing tube connected with said chamber, a venturi mounted in one of said tubes and surrounding the nozzle disposed therein, a wall extending transversely across the other tube and formed with a plurality of openings, the wall of one of which is concentric to the nozzle disposed in said tube, a venturi supported in said last mentioned opening in said transversely extending wall, a throttle for controlling the flow of carbureted air through said outlet, means for operating said throttle, a valve for controlling the flow of carbureted air from one of said mixing tubes into said conduit, means for positively operating said valve, and a valve for the other opening in said wall for admitting air from the intake through said opening into the adjacent mixing tube.

30 7. In a carburetor, the combination of a fuel supply chamber, an air intake, an outlet conduit, a pair of mixing tubes each communicating with said intake and said conduit, a nozzle disposed in each of said mixing tubes and connected with said chamber, one of said nozzles comprising inner and outer concentrically arranged tubes, the inner one of which is connected to said chamber, said inner tube terminating at a point 40 below the level of the fuel to permit the fuel to over flow into the outer tube, a valve for controlling the flow of carbureted air through said conduit, a valve for controlling the flow of carbureted air from one of said mixing tubes into said conduit, operating connections between said valves, means for operating one of said valves, a supplemental vented fuel well, and a connection between the lower end of said well and said outer nozzle tube through which said well is filled and emptied.

8. In a carburetor, the combination of a fuel supply chamber, an air intake, main and secondary mixing tubes each communicating 55 with said intake, an outlet conduit into which said tubes open, a nozzle disposed in each said mixing tube connected with said chamber, a venturi surrounding the nozzle in said main mixing tube, a throttle for controlling the flow of carbureted air through said conduit, a valve for controlling the flow of carbureted air from said secondary mixing tube into said conduit, means for operating said throttle and said valve, and means responsive to fluid pressure for supplying a

variable quantity of air from the intake around the nozzle and the venturi in said main mixing tube.

9. In a carburetor the combination of a fuel supply chamber, an air intake, an outlet conduit, a throttle for said conduit, a pair of mixing tubes between and communicating at their opposite ends respectively with said intake and said conduit, a nozzle disposed in each said mixing tube connected with said chamber, a venturi in one of said tubes, a gravity seated air valve in the mixing tube having said venturi therein and forming a by-pass therearound from said intake, and a valve for controlling the flow of carbureted air from the other of said tubes into said conduit.

10. In a carburetor, the combination with a fuel supply chamber, of a relatively small mixing tube having a fuel nozzle for low speed operations, a relatively large mixing tube having a fuel nozzle, said relatively large mixing tube being supplemental to and co-ordinated with said first mentioned mixing tube for higher speed operations, an air intake, means for admitting air from said intake to said mixing tubes, an outlet to which both said mixing tubes are connected, valves for said outlet and said supplemental mixing tube, and mechanism for admitting air to said relatively small mixing tube independently of said first mentioned air admitting means.

11. In a carburetor, the combination with a fuel supply chamber, of a relatively small mixing tube having a nozzle connected to said chamber for low speed operations, a relatively large mixing tube having a nozzle connected to said chamber, said relatively large mixing tube being supplemental to and co-ordinated with said first mentioned mixing tube for higher speed operations, an air intake, means for admitting air from said intake to said mixing tubes, an outlet to which both said mixing tubes are connected, valves for controlling in co-ordinated relationship the flow of carbureted air through said outlet and from said relatively large mixing tube to said outlet, and a valve mechanism for admitting air to said relatively small mixing tube independently of the above mentioned air admitting means, the valve of said valve mechanism being gravity seated and unseated when the suction effect of the engine overcomes its weight.

12. In a carburetor, the combination with a fuel supply chamber, of a relatively small mixing tube having a nozzle connected to said chamber and a venturi therein for low speed operations, a relatively large mixing tube having a nozzle connected to said chamber, said relatively large mixing tube being supplemental to and co-ordinated with said first mentioned mixing tube for higher speed operations, an air intake for admitting air

- 8
to said venturi and the relatively large mixing tube, an outlet to which both said mixing tubes are connected, valves for controlling in co-ordinated relationship the flow of carbureted air through said outlet and from said relatively large mixing tube to said outlet, and a valve mechanism for admitting air from said intake around said venturi into said relatively small mixing tube.
- 10 13. In a carburetor, the combination of a mixing tube of relatively small capacity having a fuel nozzle arranged to supply carbureted air for ordinary driving speeds, a mixing tube of relatively large capacity having a fuel nozzle, said relatively large mixing tube being co-ordinated with said first mentioned mixing tube to supply carbureted air supplemental to that supplied thereby for higher driving speeds, an outlet to which 15 said mixing tubes are connected, means for supplying fuel to said nozzles, a valve for controlling the flow of carbureted air from said relatively large mixing tube, means for controlling the flow of carbureted air from 20 said tubes through said outlet, said control means being disposed and arranged to permit substantially equal portions of the combustible mixture to pass to either side thereof when either the mixing tube of relatively small 25 capacity or both mixing tubes are supplying carbureted air to said outlet, and connections between said control means and said valve, whereby the latter is positively operated.
14. In a carburetor, the combination of a mixing tube of relatively small capacity, having a fuel nozzle arranged to supply carbureted air for ordinary driving speeds, a mixing tube of relatively large capacity having a fuel nozzle said relatively large mixing 30 tube being co-ordinated with said first mentioned mixing tube to supply carbureted air supplemental to that supplied thereby for higher driving speeds, an outlet to which 35 said mixing tubes are connected, means for supplying fuel to said nozzle, means for admitting air to said mixing tubes, means for admitting air to said mixing tube of relatively small capacity independently of said first mentioned air admitting means, and 40 means for controlling the flow of carbureted air from said tubes through said outlet, said control means being disposed and arranged to permit portions of the combustible mixture to pass to either side thereof from said 45 mixing tubes when either the mixing tube of relatively small capacity or both mixing tubes 50 are supplying carbureted air to said outlet.
- 55 15. In a carburetor, the combination of a fuel supply chamber, a pair of mixing tubes 60 each having a nozzle therein connected to said chamber, an air intake for supplying air to said tubes, an outlet conduit with which said mixing tubes communicate and a butterfly valve mounted to rotate in said conduit
- about an axis extending transversely thereof and disposed in a plane cutting the axes of said nozzles, a device for controlling the flow of carbureted air from one of said mixing tubes to said outlet conduit, and connections between said valve and said device, whereby the latter is positively operated.
16. In a carburetor, the combination of a fuel supply chamber, a pair of mixing tubes each having a nozzle therein connected to said chamber, an air intake for supplying air to said tubes, an outlet conduit with which said mixing tubes communicate, a butterfly valve mounted to rotate in said conduit about an axis extending transversely thereof and disposed in a plane cutting the axes of said nozzles, and valve devices disposed upon opposite sides of said plane for admitting air into one of said mixing tubes.
17. In a carburetor, the combination of an air intake, a chamber for supplying fuel, a pair of mixing chambers each having a venturi in communication with said intake and a nozzle connected to said supply chamber, an outlet conduit with which said mixing chambers communicate, a butterfly valve in said conduit secured to a shaft extending transversely thereof and disposed in a plane cutting the axes of said nozzles, a wall for closing the lower end of one of said chambers around the venturi therein, said wall being formed with an opening, and a valve device normally closing said opening and arranged to admit air from said intake into said chamber around the venturi therein.
18. In a carburetor, the combination of an air intake, a chamber for supplying fuel, a pair of mixing chambers arranged side by side parallel to each other, each including a venturi having communication with said intake and an axially arranged nozzle connected to said supply chamber, an outlet conduit with which said mixing chambers communicate, a butterfly throttle valve in said conduit secured to a shaft extending transversely thereof and disposed in a plane cutting the axes of said nozzles, a wall for closing the lower end of one of said mixing chambers around the venturi therein, said wall being formed with an opening, a valve device normally closing said opening and arranged to admit air from said intake around said venturi into the adjacent mixing chamber, a valve for controlling the flow of carbureted air from the other mixing chamber, and connections between said throttle valve and said last mentioned valve arranged to operate the latter after said throttle valve has been opened a predetermined distance.
19. A carburetor having in combination an air intake, a mixture outlet, a plurality of mixing tubes of different capacities communicating with said intake and said outlet, a plurality of air admitting means control

ling the admission of air to one of said mixing tubes under different operating conditions, a fuel chamber, fuel inlet means in each mixing tube and communicating with 5 said fuel chamber, means controlling the action of said mixing tubes so that said tubes are brought into action successively, and

means controlling the flow through said mixture outlet arranged to divide the mixture passing therethrough in equal parts under all .10 conditions of operation.

In testimony whereof, I have hereunto signed my name.

JOHN M. FLANNERY.
